UNITED STATES PATENT OFFICE.

GEORGE YOUNG PARLIER, OF CARROLLTON, GEORGIA.

STOVE-DAMPER.

1,126,652.

Specification of Letters Patent. Patented Jan. 26, 1915.

Application filed May 18, 1914. Serial No. 839,396.

To all whom it may concern:

Be it known that I, GEORGE Y. PARLIER, a citizen of the United States, residing at Carrollton, in the county of Carroll and State of Georgia, have invented a new and useful Stove-Damper, of which the following is a specification.

This invention relates to stove dampers, and aims to provide a novel and improved damper structure, which is readily operable for swinging and holding the damper, and which is unique, yet simple and convenient in construction.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the drawings accompanying this specification and forming a part thereof, the preferred embodiment of my invention is illustrated, in which:—

Figure 1 is a longitudinal sectional view of a stove having several of the improved dampers. Fig. 2 is a transverse sectional view thereof taken on the line 2—2 of Fig. 1. Fig. 3 is an enlarged fragmental view in section taken on the line 3—3 of Fig. 2.

Referring to the drawings, in which similar reference numerals designate corresponding parts throughout the several views, the numeral 4 indicates the stove casing inclosing the oven 5. A pipe 6 communicates with the flue between the casing and oven. The upper left hand corner of the oven is provided with the fire box 7 therein, and below which is situated the ash pit 8, the two being divided by the grate 9. The ash pit does not extend to the bottom of the oven so that the portion 10 of the oven chamber is situated directly below the ash pit to be directly heated thereby. The water back 11 communicates with the water tank 12 by the pipes 13 and thus provides for the supply of hot water in a manner similar to the ordinary stove. Dampers 14 and 15 are positioned at the top of the oven adjacent the sides of the fire box and swing

through the arcs as indicated in dotted lines. 55 The damper 14 is adapted to swing into the position indicated in dotted lines in Fig. 1, and when so positioned will cut the fire box off from direct communication with the flue and force the products of combustion 60 through the spaces 16, 17, 18 and 19, around the oven so that the oven will be uniformly heated. The damper 15 is used to control the area of discharge outlet for the gases.

At times it is essential that the oven be 65 more highly heated at the top than at the bottom and for this reason a third damper 20 has been provided and is located at the upper corner of the oven remote from the damper 14. With the damper 20 closed as 70 indicated in the drawing and the damper 15 open, the hot gases will circulate freely above the oven but will be prevented from entering either to the sides or below the same. 75

Each of the dampers 14, 15 and 20 comprises a damper rod 22 journaled within the casing and having one end portion protruding therefrom through an aperture or bearing 22' provided in the front side of the 80 casing. The damper plate or wing 23 is secured upon and carried by the rod 22, and a tubular member 26 is slidable upon the protruding portion of the rod 22 and is constrained against rotation thereon. 85 Complementing handle sections 24 and 27 are secured to the protruding end of the damper rod and the outer end of the tubular member, respectively, the handle sections being semi-spherical and forming a 90 hollow divided handle. A coiled wire expansion spring 28 is disposed upon the damper rod 22 between the sections of the handle to be housed within the handle, and for yieldably forcing the tubular member 26 inward or toward the stove casing. The handle section 24 of the damper rod 22 is preferably secured and held in place theron by means of a nut 25 threaded upon the end of the damper rod. The inner end 100 of the tubular member 26 and stove casing are provided with interengaging means for holding the tubular member at various angular positions to which it is swung, to thereby hold the damper at the desired position. Thus, the inner end of the tubular member 26 is provided with a pair of opposite curved fingers 29 engagable in oppo-

site arcuate series of notches 30 provided in the outer side of the stove casing. The inner end of the tubular member 26 is also provided with a radial pointer 31 coöperating with the graduated scale 32 upon the casing for indicating the position of the damper. When it is desired to swing the damper, the handle 24-27 is grasped in the hand and the handle sections are drawn together, against the tension of the spring 28, which will result in the tubular member 26 being slid outward to disengage the fingers 29 from the notches 30 and whereby the handle may be readily turned to swing the damper as desired. When the handle is released, the tubular member 26 will be slid inwardly under the influence of the spring 28, to again engage the fingers 29 with the notches 30 for holding the damper in place.

The damper actuating mechanism is convenient and efficient in construction and operation, and enables the damper to be readily adjusted and held at various adjusted positions.

Having thus fully described my invention, what I claim as new is:—

In a damper structure, a casing having a damper rod journaled therein and having one end portion protruding therefrom, a damper carried by the said rod with the casing, a tubular member slidable upon the protruding portion of the rod and constrained against rotation thereon, the inner end of the tubular member and the casing having interengageable means, complementing handle sections secured to the outer end of the tubular member and to the protruding end of the damper rod, respectively, the said handle sections forming a hollow divided handle, and an expansion spring housed within the said handle between the sections thereof.

In testimony that I claim the foregoing as my own, I have hereto affixed my signature in the presence of two witnesses.

GEORGE YOUNG PARLIER.
